BY
Rosenbaum, Stockbridge & Kornet.
ATTORNEY

UNITED STATES PATENT OFFICE.

HARRY H. KLEIN, OF NEW YORK, N. Y.

HAIR-WAVER.

1,270,623.

Specification of Letters Patent. Patented June 25, 1918.

Application filed July 10, 1917. Serial No. 179,624.

To all whom it may concern:

Be it known that I, HARRY H. KLEIN, a citizen of the United States, residing at the city of New York, in the borough of Manhattan and State of New York, have invented certain new and useful Improvements in Hair-Wavers, of which the following is a full, clear, and exact description.

My invention is designed as an improvement upon that class of hair wavers in which a rigid body is employed having a flexible cord tied or otherwise connected to one end thereof and provided with attaching means for the cord at the opposite end. The object 10 of the invention is to provide a yielding cover for the hard unyielding body portion so mounted upon the latter that there is no danger of its accidental detachment, and to provide for the connection of the flexible 15 cord to the body without the use of unsightly knots.

Other objects of the invention will hereinafter appear and the novel features thereof will be set forth in the claims.

25 In the drawings forming part of the specification;

Figure 1 is an edge view on a reduced scale of a hair waver constituting one embodiment of my invention;

30 Fig. 2 is a side elevation of the same upon a larger scale;

Fig. 3 is a side elevation showing one layer of the cover applied and illustrating the method of application;

35 Fig. 4 is a cross section on an enlarged scale on the line 4—4 of Fig. 2;

Fig. 5 is a similar section on the line 5—5 of Fig. 3;

40 Fig. 6 is a view in side elevation of the core or body partly shown in Figs. 1, 2 and 3;

Figs. 7, 8 and 9 are similar views of modified forms of cores which may be employed;

45 Fig. 10 is an enlarged cross sectional view of the core shown in Fig. 7;

Fig. 11 is a cross section on the line 11—11 of Fig. 9, and

50 Fig. 12 is a detail view showing the manner of applying the ball or knob to the knotted free end of the flexible cord.

Like reference numerals indicate like parts in the different views.

In the embodiment of my invention illustrated in Figs. 1 to 6, inclusive, the improved waver is shown as consisting of a body portion 1 composed of a core 2 having a soft cover 3 tightly applied thereto and a

flexible cord 4 connected to the body without the use of knots or separate connecting means and preferably integral with the 60 cover 3. The core 2 is shown as constructed of two strands 5 of spring metal or other suitable resilient material lying throughout the greater part of their length in close contact with each other and preferably formed 65 from a single piece of wire bent back upon itself, as shown at 6. The extremities of the strands 5 of which the core is composed may be slightly flared, as shown at 7, to permit of the ready insertion of the flexible cord 4 70 between them. Intermediate the ends of the core 2, the two strands 5 of which the same is made, are shown as flattened at 8 to form the shoulders 9. These shoulders may, of course, be otherwise formed if desired. The 75 flattening of the strands 5, however, not only produces these shoulders but also serves to increase the width and decrease the thickness of the body as a whole, which is desirable as the hair is wound directly upon the body of 80 the waver. As shown in Fig. 4, the cover 3 surrounding the core 2 is of double thickness, and as shown in Fig. 2, the cord 4 is integral with this cover, being a continuation of the outer layer thereof. The cover 85 is applied by braiding the same over the core by employing the ordinary circular braiding machine with a slight modification therein designed merely for the purpose of permitting a reversal of the direction of the braiding operation, to be referred to later. I start the braiding operation a short distance beyond the looped end 6 of the core and produce a short section 10 of tubular braid 90 before the braiding strands reach the core. 95 The braiding operation is continued with a single layer of braid tightly applied to the outer surface of the core 2 until a point is reached a short distance from the flared ends 7 of the core, as illustrated in Fig. 3 of the drawing. The direction of feed of the braiding strands is now reversed and a second layer of the braid is tightly applied to the outer surface of the first layer until the core and the short section 10 is covered with this second layer. After this the braiding operation is continued to produce the flexible cord 4. By reversing the direction of feed of the braiding strands at a point near the separated extremities of the core 2, a neat finish is produced at this point without any danger of the cover fraying out; by making a double layer of braid upon the core 2 a soft yielding surface is provided 110

upon which the hair is wound when the device is in use, and by continuing the braiding operation beyond the short section 10 to produce the flexible cord 4, the latter is 5 made an integral part of the cover 3, and is thus connected to the body of the device without the necessity of tying knots or the use of separate connecting means. The braided cover 3 being tightly applied to the 10 core 2, serves to hold the two strands 5 of said core in close relation with each other so as to provide for the frictional attachment of the free end of the cord 4 by inserting the same between the exposed ends of 15 the strands 5, and if desired winding the same around said strands. The cover 3 extends beyond the shoulders 9 and is prevented from detachment from the core 2 by its engagement with said shoulders.

20 The free end of the cord 4 is knotted, as shown at 11, and around this knot is clamped a hollow finishing ball 12 made in a well-known way from a slotted metallic disk. This not only covers and conceals the knot, 25 but prevents the fraying out of the strands of the braid at the end of the cord.

The core upon which the cover is braided or otherwise applied is susceptible of a wide range of modification. In Fig. 7 of the 30 drawing, for example, the core 2^a is shown as made from a flat strip of metal, celluloid or other suitable material having the shoulders 9^a thereon which are engaged by the cover, and the forked or bifurcated ends 35 7^a for the attachment of the free end of the flexible cord.

In Fig. 8, the core 2^b is somewhat similar to the core 2 of Fig. 6, but the shoulders 9^b and the increased width of the body are attained by bending the two strands of the 40 core at points near the opposite ends thereof so as to separate the central portions of these strands. With this form of core, however, a filler 13 is preferably employed between the separated portions of the strands 45 to prevent the same from compressing when the device is in use and the hair is wound thereon.

In Fig. 9, the core 2^c is similar to that 50 illustrated in Fig. 8, the same differing therefrom in that the filler 13^a is formed in one piece with the wire of which the core 2^c is made.

Other modifications, not only of the core 55 but of other features of my invention, may, of course, be made, and I do not desire to be limited to any of the details of construction herein shown and described, except as I limit myself in the following claims.

60 I claim:

1. A hair waver comprising a body consisting of a core having lateral shoulders or projections thereon and having cord-attach-

ing means at one end, and a yielding cover tightly applied to said core and engaging 65 said shoulders, and a flexible cord integral with said cover.

2. A hair waver comprising a body consisting of a core made up of a plurality of resilient strands with lateral shoulders or 70 projections formed thereon, and a fabric cover tightly applied to said core engaging said shoulders and retaining said strands in close relation to each other adjacent said shoulders, and a flexible cord integral with 75 said cover and extending outwardly beyond one end of said core.

3. A hair waver comprising a body consisting of a core made up of a plurality of resilient strands shaped to produce lateral 80 shoulders and with its width greater than its thickness, and a fabric cover tightly applied to said core engaging said shoulders and holding said strands in close relation to each other adjacent said shoulders, and a 85 flexible cord integral with said cover and extending outwardly beyond one end of said core.

4. A hair waver comprising a body consisting of a core made up of a plurality of 90 resilient strands bent near their opposite ends to separate their intermediate portions and to form lateral shoulders, a filler located between the separated portions of said strands and a fabric cover tightly wound 95 upon said core engaging said shoulders and holding said strands in close relation to each other adjacent said shoulders, and a flexible cord integral with said cover.

5. A hair waver comprising a body consisting of a core made up of a plurality of resilient strands bent near their opposite ends to separate their intermediate portions and to form lateral shoulders, a wire filler located between the separated portions of 100 said strands, the same being bent to form engaging portions for the inner surfaces of said strands, and a fabric cover tightly applied to said core engaging the shoulders thereon and holding the free ends thereof in 105 close relation to each other, and a flexible cord integral with said cover.

6. A hair waver comprising a body consisting of a core having cord-attaching means at one end and a braided cover for the 115 core, said cover being applied by braiding one layer from one end of the core to a point adjacent the opposite end and then reversing the direction and braiding a second layer upon the first, and a flexible cord 120 produced by continuing the braiding operation beyond the core.

In witness whereof I subscribe my signature.

HARRY H. KLEIN.
